MICHAEL HOLDENER, OF BELLEVILLE, ILLINOIS.

Letters Patent No. 86,671, dated February 9, 1869.

IMPROVEMENT IN COOKING-STOVES.

The Schedule referred to in these Letters Patent and making part of the same.

To all whom it may concern.

Be it known that I, MICHAEL HOLDENER, of Belleville, in the county of St. Clair, and State of Illinois, have invented a new and useful Improvement in Cooking-Stoves; and I do hereby declare that the following is a full, clear, and exact description thereof, reference being had to the accompanying drawings, making a part of this specification, in which—

Figure 1 is an elevation of one side of my improved cooking-stove.

Figure 2 is a longitudinal section, taken in a vertical plane through the centre of the improved stove.

Figure 3 is a transverse section, taken through the improved stove in the vertical plane indicated by line xx in fig. 2.

Similar letters of reference indicate corresponding parts in the several figures.

The object of this invention is to so construct a cooking-stove that a tight oven or chamber is formed on top of the plate which has heretofore constituted the top of the stove, the top plate of which oven is perforated with large boiler-holes, and the side or sides of which oven are provided with a door or doors, for allowing access to the interior of the oven, thereby forming a chamber whose bottom plate will be acted upon by the direct heat of the fire, so that boilers of various kinds can be subjected to heat without having their walls injured and sooted, and so that articles placed in this oven, or chamber, can be heated or more quickly cooked than could be done in the oven in the body of the stove, all as will be hereinafter explained.

Another object of the invention is to so combine a perforated top oven with a stove which has a bottom oven, made with an imperforated double-top wall, that provision is made for cleaning the flues of such stove, as hereinafter explained.

To enable others skilled in the art to understand my invention, I will describe its construction and operation.

By reference to the accompanying drawings, it will be seen that the general form of the cooking-stove is the same as some of the well-known kitchen-cooks in common use; that is to say—

A A represent the outer walls of a rectangular stove;

B, the oven;

C, the fire-chamber;

D, the ash-pit;

E, the escape-flue; and

a b, the flues which conduct the products of combustion around the oven B when the damper S is shut.

The flame from the fire-chamber C acts directly against the top plate A, which, in my stove, is imperforated.

At the back part of the stove, directly below the ascending-flue a, at the back of the oven, is an opening, r, through the bottom plate of the stove, which opening leads into a drawer, K.

As the top plate of the stove is imperforated, for a

reason hereinafter explained, the opening, r, and drawer K, with a valve at t, will allow access to the flues of the stove, for cleaning them out.

In stoves which have perforated top plates, access can be readily had to the flues through the perforations made through said plates, but, with the imperforated-plate stoves, the provision above described becomes necessary to clean the flues.

On top of this imperforated-top stove, I construct a chamber G, the top plate G' of which is perforated for receiving the boilers H, and through one side is an opening, closed by a door, J, for affording access to the interior of said chamber.

The walls of this upper chamber are held down in place by means of vertical rods e, and the flue-pipe E passes up through this chamber, as clearly shown in figs. 2 and 3.

When pots or boilers are not used on top of chamber G, the holes through plate G' will be closed by covers, as shown in the drawings.

The boilers or pots H are preferably made with long, contracted portions, which will extend down to the plate A of the stove, so that the bottoms of these vessels shall rest or impinge upon said plate, and thus receive a more intense heat than they otherwise would.

It will be seen, from the above description, that the chamber G not only serves as a means for protecting the vessels H from the injurious effects of flame, but that this chamber forms a supplemental oven, which is well adapted for warming articles or for various cooking-purposes where a bottom heat is desirable.

I am aware that it is not new, broadly considered, to protect vessels placed upon the top plates of stoves from the direct action of flame and smoke, as this has been done by making imperforated depressions in the top plates of stoves, for receiving vessels; also by using depressed dishes; and therefore I do not claim to be the first inventor of this principle.

I do not claim the employment of a diaphragm, or partition, between the top of an ordinary oven and the perforated top plate of a cook-stove; nor do I claim arranging an oven or circular drum, with closed top plate, and through which the flame is intended to circulate, upon the top of such a stove, for these things are shown substantially in Mott's patent of 1837, and also, in part, in the patents of Wilson, 1866, and Dickinson, 1835;

What I do claim as an improvement on the inventions shown in said patents, and which I desire to secure by Letters Patent, is—

1. The employment of the oven G, constructed with a perforated top plate, G', and with one or more doors J in its sides, in combination with the imperforated-top plate of the stove A, all in such manner that the shoulders of the pots and kettles overhang a portion of the top of the oven G, while their bottoms rest upon the imperforated-top plate of the stove, and also so that the process of baking may be carried on at pleasure in said oven, substantially as described.

2. An oven, with boiler or kettle-holes in its top, applied to a cook-stove in such a manner that it can be used solely for cooking or roasting, by closing its pot or kettle-holes, and, for heating water in kettles or vessels, by opening said holes and inserting the kettle-bottoms through the same, all substantially as described.

3. A perforated-top oven, G, in combination with a stove, which has an imperforated top, and also a provision for cleaning its flues, substantially as described.

MICHAEL HOLDENER.
